UNITED STATES PATENT OFFICE.

EDWARD N. MOOR, OF OAKLAND, CALIFORNIA.

INTERIOR-SLOTTING ATTACHMENT FOR LATHES.

1,333,210.

Specification of Letters Patent.

Patented Mar. 9, 1920.

Application filed February 18, 1919. Serial No. 277,719.

To all whom it may concern:

Be it known that I, EDWARD N. MOOR, a citizen of the United States, residing at Oakland, in the county of Alameda and State of California, have invented certain new and useful Improvements in Interior-Slotting Attachments for Lathes, of which the following is a specification.

My invention relates generally to lathe attachments and particularly to an appliance or device adapted for ready attachment to and removal from the cross-slide of a lathe, and the function of which is to cut or plane an interior key-way, groove or slot in the shaft-hole of a part, such, for example, as a gear, which has been previously turned and milled in the chuck of the lathe, the slotting being done while said part or gear is still in the chuck, without removing or disturbing it.

The object of my invention is to provide a simple and effective appliance for this purpose, and to this end my invention consists in the novel interior slotting lathe-attachment which I shall hereinafter fully describe by reference to the accompanying drawings, in which—

Figure 1 is a plan view of a lathe, in part, showing my attachment applied there-
30 to.

Fig. 2 is a side elevation of the same.

Fig. 3 is a plan view of my attachment, enlarged, with respect to the showing in Figs. 1 and 2, the lever arm being omitted.

Fig. 4 is a side view of the same.

Fig. 5 is a front end view of same.

I have not deemed it necessary to illustrate the lathe in full detail, it being sufficient to indicate its bed 1, its head stock 2, head-stock spindle 2', speed-change pulleys 3, lead-gears 3', lead-screw 4, apron or carriage 5, hand-wheel 5' for the carriage and cross-slide 6, with its hand wheel 6'.

In the chuck 7, I have illustrated a gear 8 which may represent the part or work, in the shaft-hole 9 of which the key-way, groove, or slot, indicated at 9', in Fig. 2, is to be made, after said gear has been previously finished and while it is still in the chuck.

My attachment comprises a body or stock 10 the base of which is set down upon the cross-slide 6, from which slide the ordinary tool-post has been temporarily removed.

The stock 10 is removably fitted and secured to the cross slide by the headed-bolt 11 and

nut 12. The stock 10 is vertically longitudinally channelled at 13, as seen best in Fig. 5, and to one wall of this channel is fitted and secured by screws 14, a fixed rack 15. 60 To the opposite wall of the channel is fitted the longitudinally reciprocative cutter bar 16, to the inner face of which is secured by screws 17, the rack 18 which is thus a part of the bar. In one end of the bar 16 65 is fitted in any approved manner the mandrel 19 carrying the cutter or planer bit 20.

A cover plate 21 is secured by screws 22 on top of the stock 10. This cover plate has a longitudinal slot 23 overlying the channel 70 13 of the stock, and said slot at one end has a circular enlargement 24.

A pinion 25 is adapted to be inserted and removed through the enlargement 24, and said pinion engages both racks 15 and 18. 75 The pinion has a square stud 26 which plays in the slot 23 of the cover plate and rises therethrough. Upon this stud is fitted the operating lever arm 27, by which the pinion is rotated about its traveling axis as it 80 moves forward or back in the fixed rack 15 and thereby reciprocates the cutter bar 16 through its rack 18.

The operation of the device is as fol-
85 lows:—

After the gear 8 has been turned and milled in the lathe and while it is still in the chuck, I remove the ordinary tool-post from the cross-slide of the lathe and substitute the stock 10. Then by means of the 90 lathe carriage 5 I move the device up to the work, and by means of the cross-slide 6, set it over so that the cutter or planer-bit 20 is in position to make the first cut of the slot 9' in the wall of the shaft hole 9 of 95 the gear 8. Then by operating the lever arm 27, the cutter bar 16 is forced forward to effect the first cut, and is withdrawn by the opposite movement of the lever-arm. Succeeding cuts are similarly made, as the 100 tool is fed sidewise by the cross-slide 6. As my invention lies essentially in the attachment to the cross slide of a lathe, of a stock, carrying a reciprocative cutter-car-
rying bar, adapted to plane out an interior 105 slot by linear movement, it is obvious that various mechanical transmissions may be applied by which the reciprocation of the cutter bar may be effected. I do not therefore confine myself to the means here shown, 110 except as hereinafter specifically claimed, but I may state that the transmission above

described comprising the fixed rack, the movable rack and the traveling pinion is of advantage in that it enables me to make a compact device by having the pinion of relatively small diameter for relatively large movement of the cutter bar.

The enlargement 24 in the slot 23 of the cover-plate 22, not only permits the insertion and removal of the pinion, but also provides for the initial engagement of the pinion with the rack 18 of the cutter bar at such point as may be required by the desired amount of projection of said bar.

I claim:

1. An interior slotting attachment for lathes, comprising a longitudinally channeled stock provided with means for detachably fitting it on the cross-slide of the lathe; a slotted cover-plate fitted to the stock and overlying its channel; a reciprocative cutter-bar mounted in the covered channel of said stock and adapted to carry a slotting tool; a rack carried by the cutter bar; a pinion housed within the covered channel of the stock for reciprocating the cutter-bar; and means operating through the slotted cover plate for rotating the pinion.

2. An interior slotting attachment for lathes, comprising a longitudinally channeled stock provided with means for detachably fitting it on the cross-slide of the lathe; a slotted cover-plate fitted to the stock and overlying its channel; a recipro-

cative cutter-bar mounted in one side of the covered channel of the stock and adapted to carry a slotting tool; a rack fixed in the other side of the covered stock-channel; a rack on the opposing face of the cutter bar; a traveling pinion housed within the covered channel engaging both racks; and means operating through the slotted cover plate for rotating said pinion.

3. An interior slotting attachment for lathes, comprising a longitudinally channeled stock provided with means for detachably fitting it on the cross-slide of the lathe; a reciprocative cutter-bar mounted in one side of the channel of the stock and adapted to carry a slotting tool; a rack fixed in the other side of the stock-channel; a rack on the opposite face of the cutter bar; a traveling pinion within the stock-channel engaging both racks; a cover plate fitted to the top of the stock and overlying its channel to house in the racks and pinion, said plate having a longitudinal slot with an enlargement to admit the pinion; and a lever arm fitted to the pinion through the cover-plate slot, for rotating said pinion.

In testimony whereof I have signed my name to this specification in the presence of two subscribing witnesses.

EDWARD N. MOOR.
